UNITED STATES PATENT OFFICE

FRANK E. MARCY, OF SAN DIEGO, CALIFORNIA

MILL

Application filed April 30, 1928. Serial No. 273,803.

My invention relates to an improvement in mills of the type wherein balls, rods, pebbles or other reducing medium are confined within a drum with the material to be reduced, the rotation of the drum and its contained load on its bearings reducing the material by impact and attrition.

One of the objects of the present invention is the provision of a mill of the type above generally referred to in which a construction is employed which will facilitate unloading or emptying of the mill.

Another object of the present invention is to provide a mill of the type above referred to in which a grate is provided adjacent the discharge end thereof, means being provided for introducing water into the mill drum adjacent the grate so as to flush the fines, i. e., material which has been reduced to the desired degree of fineness, through the grate, thereby reducing the amount of water required to be introduced with the load, and hence increasing the reducing action and efficiency of the mill.

25 A still further object of the invention is the provision of a shell or wall liner which is of improved and novel construction.

I am aware that it has been proposed prior to the present invention to provide mills with 30 a shell manhole but in such structures it is customary to protect the cover with a liner secured to the cover only. This is unsatisfactory, however, in that the shell liner must be cut to accommodate this cover, and difficulty has been experienced in holding the liner securely attached to the cover.

The present construction provides a mill in which the necessity of a separate liner for the manhole cover is eliminated, the shell liner itself being extended across and protecting the cover therefor. In emptying the mill it is merely necessary to enter the interior of the mill, remove the shell liner covering the manhole opening, and then to rotate the mill 45 for a partial turn to dump the load.

The present invention provides also a structure in which provision is made for feeding water to the interior of the mill adjacent the inner face of the grate to sluice the fines 50 therethrough, thereby increasing the dis-

charge of reduced material and reducing the quantity of water heretofore necessarily fed to the mill with the material to be reduced. A reduction in the amount of water fed to the mill necessarily reduces the cushioning effect of the pulp on the reducing medium and increases the reducing action accordingly.

In the accompanying drawings, Fig. 1 shows in longitudinal sectional elevation a mill embodying my invention;

Fig. 2 is a section transverse of Fig. 1 and facing the discharge end of the mill; and

Fig. 3 shows in perspective a section of the improved shell liner employed.

Referring to the drawings in detail, 1 designates the shell or drum of the mill. This drum which is appreciably greater in length than diameter is provided with feed head 2, discharge head 3, feed trunnion 4 and discharge trunnion 5. The trunnions are mounted in trunnion bearings 6 and 7, respectively.

The mill drum may be rotated by a drive of conventional design well known to those skilled in this art and hence the same has not been illustrated.

The feed head is provided with manholes 8 and covers 9 therefor bolted on in the usual way.

The shell or wall of the drum 1 is provided with sectional wall liners 10, one of which has been illustrated in perspective in Fig. 3. These liners are of a new construction and held in place in the mill by bolts 11.

As will be seen from Figs. 2 and 3 the shell or wall liners are of undulating or wave form not only on the inner or wearing surface or face 12 but on the outer or underside 13 as well, that is to say on the side adjacent the shell or wall of the drum. Preferably the undulations on the underside of the liner sections are offset slightly with respect to the undulations on the wearing surface so as to compensate for the wear on the liner due to the action of the mill load thereon. For instance an inspection of Fig. 2 will show that the depressions 14 on the wearing surface 12 are slightly in advance of the corresponding depressions 15 on the underside of the liner, the mill, it is assumed,

rotating in the direction of the arrow on Fig. 2.

The edges of the wall liner sections are beveled as indicated at 16 and 17 so that the liner sections may be readily placed or set and yet provide a good joint.

Adjacent the discharge head 3 of the mill I provide grate sectors 18, assembled about a central discharge cone 19. The grate sectors are held in place by clamp bars 20 and end clamp members 21. Between the grate sectors just described and the discharge head 3 are the usual lifters 22.

Extending into the mill from the exterior thereof is a water pipe 23, this pipe passing through the central discharge cone 19 as shown at 24 to the inner side of the grate, thereby providing means adjacent the grate for introducing water into the mill at the inner face of the grate to sluice the fines therethrough.

In operation the mill is rotated in the trunnion bearings 6 and 7, material being fed into the mill through the feed trunnion 4. As the mill is rotated in the direction of the arrow on Fig. 2 for instance the load including the reducing medium is carried upwardly finally tumbling and cascading toward the bottom of the mill drum, to effect reduction of the material by impact and attrition. The wave formation of the liners assists in this upward movement, as will be understood. As the mill rotates the material is constantly worked toward the grate sectors 18 and the fines, i. e., the material which has been sufficiently reduced, works through the grate, is elevated by the lifters 17 and discharged from the mill through the trunnion 5. To promote the passage of the fines through the grate sectors water may be introduced to the interior of the mill adjacent the inner face of the grates while the mill is in operation through the pipe 23, this water sluicing the fines through the grates. This permits of operation with the introduction of less water with the load than is customary in present practice, thereby reducing the amount of pulp in the mill and to the same degree reducing the cushioning effect of this pulp, and permitting the reducing medium to act with that much more efficiency upon the material being reduced. As a result, therefore, the efficiency of the mill will be increased.

The liners by reason of their wave formation on both faces may be rolled instead of cast, and by offsetting these formations, as above explained, wear on the grinding surface of the liner is compensated for and hence the life of the liner is prolonged to that extent, and renewal of the liner sections is required less frequently than with liner sections heretofore employed.

It will be apparent also that I have provided a mill structure in which the shell liners extend across the manhole opening, thus

eliminating the trouble experienced heretofore with that type of mill in which the shell manhole cover has been lined.

What I claim is:

1. A mill comprising a drum, the shell of which is provided with a manhole opening, and a liner for the drum shell overlying said manhole opening. 70

2. A mill comprising a drum, the shell of which is provided with a manhole opening, 75 sectional liners for said shell, at least one of said sections extending across said manhole opening.

3. A mill comprising a shell, a feed head and a discharge head, one of said heads and the shell being provided with a manhole opening, and a liner for said shell extending across the manhole opening in the shell. 80

4. A rolled steel liner for mills having a wave or undulating surface on its wearing a face leading or offset to a wave or undulating surface provided on the opposite face of the liner, said liner being of the same cross-section throughout its length. 85

5. A rolled steel liner for mill drum shells, 90 comprising liner sections extending lengthwise of the drum, the adjacent edges of the liner sections being beveled to facilitate placement and removal of the sections, each section being provided with wave or undulating surfaces on its wearing face and its inner face, the formation on the wearing face leading the formation on the inner face. 95

6. The combination of a mill drum, flat grating surfaces adjacent the discharge end of said drum, a cone centrally located within said drum, said grating sectors being so assembled about said cone as to lie in the one plane and extend radially of the mill drum, and a water pipe passing through said cone from the exterior of the mill and terminating at such a point with reference to the inner conical face of the cone and the inner face of the grating sectors that water issuing from said pipe will be directed upon the inner faces of 110 the grating sectors. 105

This specification signed this 21 day of April, 1928.

FRANK E. MARCY.
